UNITED STATES PATENT OFFICE.

JOSEPH P. CARSON, OF RICHMOND, VIRGINIA, ASSIGNOR TO AMERICAN MOTOR EQUIPMENT CORPORATION, OF RICHMOND, VIRGINIA, A CORPORATION OF VIRGINIA.

AUTOMOBILE HEADLIGHT.

Application filed November 5, 1924, Serial No. 747,942. Renewed November 5, 1927.

My invention relates to new and useful improvements in vehicle headlights, and has for its object to provide a headlight which will so confine and direct the rays of light emanating from the lamp and reflector, that while said rays will serve to clearly illuminate the entire road, on both sides, and for a long distance ahead, yet to retain such control over said rays that they will create no glare, which will reach the eyes of an approaching motorist or pedestrian, whether in front, or on the side.

Heretofore the lamps as well as the specially constructed lenses, designed to overcome this blinding effect of the strong rays, have in diminishing the glare, also cut down the amount of light projected by the lamp and none have succeeded in satisfactorily eliminating the dazzling glare, from the bulb or the reflector or from both.

To accomplish this end, I have constructed a headlight which serves to effectually conceal the sources of the light, and at the same time to so direct the rays, that the entire road surface will be at all times satisfactorily illuminated, without the blinding glare which renders the motor headlights now in general use, both disagreeable and at times dangerous.

With the above and other objects in view, which will appear as the description proceeds, my invention consists in the novel features herein set forth, illustrated in the accompanying drawings and more particularly pointed out in the appended claims.

Referring to the drawings, in which numerals of like character designate similar parts through the several views;

Fig. 1 is a sectional view of the headlight.

Fig. 2 is a view looking down upon the light, showing the translucent deflecting portion of the top, and the horizontal partition and inclined plate in dotted lines, and

Fig. 3 is a front view of the light.

In the drawings, 1 designates a lamp comprising an ordinary reflector 2 and bulb 3, the edges 4 of said lamp extending longitudinally for a slight distance and being adapted to fit firmly into the elongated hood 5 which at the rear end is cylindrical and at the other end substantially U-shape as shown at 6, Fig. 3. This hood 5 is composed of metal with an inner surface of a non-reflecting character, having inserted in the

portion of the top at the end 6, a window 55 7 of translucent material, preferably glass, of any desired color or shade, frosted or similarly treated to render it non-reflecting and non-transparent for the purposes to be hereinafter described. This translucent window 7 is set at an angle to the rays of light, and downwardly toward the front and forming the upper part of the mouth 8 of the hood 5, as shown in Fig. 1.

In this hood 5 at approximately its longitudinal center, I provide a partition 9, preferably of thin metal, non-reflecting on top and reflecting on its lower surface, which is set longitudinally to the rays of light, and parallel with the bottom of said hood, running substantially the entire length of the hood. Below this partition 9, I provide a second partition or plate 11, downwardly inclined toward the end 6 of the hood 5. Said plate may be composed of thin metal, 75 but is preferably made of some translucent material similar to the window 7. In this particular embodiment of my invention, I have shown lugs 10, on the inner surface of the hood 5, for securing the partitions 80 in place, but any suitable means may be employed for this purpose.

In order to exclude any dust or rain, it may be desirable to provide a lens or translucent cover 12, for the mouth 8 of the hood. 85

The assembled headlights are secured to the forward end of a vehicle by any desired means, with the reflector end slightly higher than the mouth end, thus causing the deflected translucent top 7, the horizontal 90 partition 9 and the inclined plate 11 to effectually conceal the sources of light, namely the bulb and reflector from the line of vision X, and avoid all glare. The translucent portion 7 of the top of the hood and the 95 plate 11, will allow a certain amount of softened light rays to pass through and project from the upper and lower portions of the hood 5 as indicated by the dotted lines in Fig. 1. These latter rays will reach the 100 eyes of an approaching driver, but are not strong enough to cause any discomfort.

It is obvious from Fig. 1, that when the headlight is in place on a vehicle at an angle as stated, the sources of light, and all 105 reflecting surfaces will be entirely concealed from the line of vision of an approaching driver, due to the combined effect of the

translucent top 7, the horizontal partition 9 and the inclined plate 11, as shown by the line X in Fig. 1, while the softened rays will produce a glow which is beneficial to both drivers.

From the foregoing, it is believed that my invention may be clearly understood without further description, it being borne in mind that numerous changes may be made in the details of construction without departing from the spirit of the invention as disclosed in the appended claims. For instance, I may construct my lamp so that the entire top of the hood will be translucent, or a third plate or partition may be introduced within the hood.

It is also obvious that the lamp body and hood may be integral, although the construction hereinabove described is preferred, in order that the bulb and reflector may be removed for adjustments, or used for a trouble light, in case of need.

What I claim and desire to secure by Letters Patent is:—

25 1. A vehicle headlight comprising a lamp, a hood, means in the top of said hood and angularly disposed with relation thereto, for confining and transforming portions of the light rays and means within said hood parallel with the under wall thereof, for confining and deflecting other portions of said light rays.

35 2. A vehicle headlight comprising a lamp, a hood, means in the top of said hood and angularly disposed with relation thereto, for confining and transforming portions of the light rays, means within said hood parallel with the under wall thereof, for confining and deflecting other portions of said light rays and further means angularly disposed to said last named means, for confining and transforming other light rays.

40 3. A hood as claimed in claim 2, wherein portions of the inner surface of the walls of said hood are of a non-reflecting character.

45 4. A vehicle headlight, comprising a lamp, a hood, a light ray confining and transforming insert of translucent material in the top of said hood, angularly disposed with relation to said rays, and a light ray confining and reflecting plate of opaque material non-reflecting on the upper surface and reflecting

on the lower surface, set horizontal to the rays of light.

55

5. A vehicle headlight comprising a lamp, a hood removably secured to said lamp, a light ray confining and transforming insert of translucent material in the top of said hood, angularly disposed with relation to said light rays, and a light ray confining and reflecting plate of opaque material non-reflecting on the upper side and reflecting on the lower side, set horizontal to the rays of light.

60

6. A vehicle headlight comprising a lamp, a hood, a light ray confining and transforming top on said hood, and angularly disposed with relation thereto, said top for said hood being composed of glass frosted or otherwise treated on at least one side thereof, whereby the strong rays emanating from the source of light passing through said top will be softened, a light ray confining and deflecting plate of opaque material, non-reflecting on the upper surface and reflecting on the lower surface set within said hood, horizontal to the rays of light, and a second plate of translucent material below said horizontal plate and at an angle thereto.

70

7. In combination with a vehicle, a headlight secured thereto at a downward angle, said headlight comprising a lamp, a hood, a light ray confining and transforming top of translucent material on said hood, and a light confining and deflecting plate of opaque material set within said hood, the said plate being set horizontal to the rays of light emanating from said lamp, and a second plate of translucent material below said horizontal plate and at an angle thereto.

75

8. A hood for a headlight comprising a cylindrical elongated body, an insert of translucent material in the top of said body and angularly disposed with relation thereto, a plate of opaque material, the lower surface of which is of a reflecting character, within said body and a second plate of translucent material beneath said last named plate

80

and angularly disposed with relation thereto, whereby the direct rays are projected forwardly and below the line of vision of any one approaching, and the transformed rays are projected upwardly and forwardly.

85

In testimony whereof I affix my signature.
JOSEPH P. CARSON.
